United States Patent [19]

Peterson et al.

[11] Patent Number: Des. 301,837

[45] Date of Patent: ** Jun. 27, 1989

[54] BOTTLE OR SIMILAR ARTICLE

[75] Inventors: Ronald A. Peterson, Fairfield County, Conn.; Heidi Mohrmann-Tidwell, New York County, N.Y.

[73] Assignee: S. C. Johnson & Son, Inc., Racine, Wis.

[**] Term: 14 Years

[21] Appl. No.: 811,265

[22] Filed: Dec. 20, 1985

[52] U.S. Cl. D9/377

[58] Field of Search ..... D9/377, 403, 413, 410, D9/370, 489; 215/1 R, 1 C
